UNITED STATES PATENT OFFICE

FRANK T. WENTWORTH, OF BEVERLY, MASSACHUSETTS, ASSIGNOR TO UNITED SHOE MACHINERY CORPORATION, OF PATERSON, NEW JERSEY, A CORPORATION OF NEW JERSEY

BUTTONHOLE MAKING MACHINE

Application filed March 1, 1928. Serial No. 258,222.

The invention relates to buttonhole making machines and more particularly to the mechanism for cutting the buttonhole slit in the work.

5 The primary object of the invention is to simplify and improve the construction of the mechanism for cutting the buttonhole slit in machines of this description.

Other objects of the invention more generally are to provide a novel and improved die cutter which while particularly adapted for use with a socket clamp in the buttonhole making machine hereinafter described, is also adapted for use in other types of machines employing die cutters of the same general description.

With these objects in view, one feature of the invention consists in the provision of a simplified and improved cutter mechanism 20 which is particularly adapted for use in a buttonhole making machine and comprises a cutter having the shape of a flattened tube and clamping members or plates arranged on either side of the cutter adapted to fit in the socket clamp of the cutter lever or carrier of the machine and hold the cutter securely in position through the pressure exerted on the clamping members by the socket clamp.

The several features of the invention consist also in the devices, combinations and arrangement of parts hereinafter described and claimed and together with the advantages to be obtained thereby should be readily understood by one skilled in the art from the following description taken in connection with the accompanying drawings which illustrate the preferred embodiment of the invention in a buttonhole sewing machine similar to that disclosed in the patent to G. S. Hill, No. 1,063,880, patented June 3, 1913.

In the drawings, Fig. 1 is a right side elevation partly in section, only so much of the machine being illustrated as is necessary to show the connection of the present invention therewith; Fig. 2 is a detail sectional view taken on the line 2—2 of Fig. 1; and Fig. 3 is a perspective view of the cutter blade and the clamping members for holding it in the socket clamp.

50 The machine illustrated comprises gen-

erally a work clamp 4 for holding the material to be operated upon, a cutter 6 for cutting a buttonhole in the material, and stitch forming mechanism comprising a straight-eye-pointed upper needle 8, a curved-eye-pointed under needle 10, and a cooperating looper 12. For a detailed description of the operation of these parts in forming a buttonhole and of the actuating mechanism therefor, reference may be had to the patent to Hill above referred to.

The die cutter which forms more specifically the subject matter of the present invention comprises the cutter blade 6 and two clamping members 14 and 16 which are arranged one on each side of the cutter blade and have their outer faces shaped to fit into a socket clamp 18. This clamp is formed on the end of the clamping lever 20 and forms a part of the ordinary construction of the buttonhole sewing machine described in the patent to Hill above referred to. The die cutter is clamped securely in position by means of the clamping screw 22 which is provided for tightening the jaws of the socket clamp 18.

The cutter blade 6 employed in the preferred form of the invention has the shape of a flattened tube sharpened at one end to form a cutting edge of the desired pattern. 80 A blade formed in this manner has the advantage that it is simple in construction, is inexpensive to manufacture, and may readily be replaced when worn out. In order to insure that the blade is held securely in position, the clamping members 14 and 16 are provided with corresponding recesses indicated at 24 and 26 so that the blade is securely held against sidewise or endwise displacement during the cutting operation. To further insure that the parts are locked rigidly in position, and also to assist in the assembly of the die cutter, a small pin 28 is formed on the clamping member 14 and is adapted to engage with a corresponding recess in the 85 clamping member 16.

The waste material which is gathered in cutting the buttonhole slits with the usual form cutters cast in a single unit is carried off by being forced up through the hollow 90

- interior of the cutter and is then carried away through a channel 30 formed in the cutter lever 20. With the hollow cutter herein disclosed, the waste material is carried off in this manner, the parts of the die cutter being so designed for this purpose that the upper end of the cutter blade 6 registers with the channel 30 and the clamping members 14 and 16 are designed to permit a free passage of the waste material from the cutter tube into the channel while at the same time affording a sufficient support to the upper end of the cutter against endwise strain during the buttonhole making operation.
- 15 The nature and scope of the invention having been indicated and one embodiment thereof specifically described, what is claimed is:
1. In a buttonhole making machine the combination with a cutter lever of a cutter having the shape of a flattened tube, a socket clamp formed in the cutter lever, and clamping members arranged on opposite sides of the cutter adapted to be held in the socket clamp to clamp the cutter rigidly in position.
  2. In a buttonhole making machine the combination with a cutter lever of a cutter having the shape of a flattened tube to permit the ejection of waste material through the interior of the tube, a socket clamp formed in the cutter lever, clamping members arranged on opposite sides of the cutter and adapted to be held in the socket clamp to clamp the cutter rigidly in position, and a channel in the cutter lever connecting with the cutter to carry away the waste material.
  3. In a buttonhole making machine the combination with a cutter block and cutter lever of a cutter having the shape of a flattened tube to permit the carrying off of waste material, a socket clamp formed in the cutter lever, clamping members arranged on each side of the cutter recessed to hold the cutter securely in position and adapted to be held in the socket clamp to clamp the cutter in position, and a channel formed in the cutter lever adapted to register with the upper end of the cutter tube.
  4. A die comprising a cutter having the shape of a flattened tube to permit the carrying away of waste material and two clamping members arranged on either side of the cutter adapted to engage in the socket of a die holder to clamp the cutter rigidly in position with the end of the cutter tube in register with a corresponding channel in the die holder.

In testimony whereof I have signed my name to this specification.

FRANK T. WENTWORTH.
